[57] CLAIM

The ornamental design for an examination table, as shown.

DESCRIPTION

FIG. 1 is a perspective view of an examination table, showing our new design;

FIG. 2 is a front elevational view of the examination table;

FIG. 3 is a side elevational view of the examination table;

FIG. 4 is a rear elevational view of the examination table;

FIG. 5 is a side elevational view thereof, opposite that shown in FIG. 3;

FIG. 6 is a side elevational view thereof, in reclined position;

FIG. 7 is a side elevational view thereof, in partially reclined position; and,

FIG. 8 is a top plan view thereof, in reclined position. The cord portion is fragmentarily shown in FIGS. 1, 2, 4 and 5 for ease of illustration and is understood to repeat uniformly throughout the broken line area.
